(57) **CLAIM**

The ornamental design for a sleeve for small glass vessel, substantially as shown.

DESCRIPTION

FIG. 1 is a perspective view of a sleeve for small glass vessel, according to our design;

FIG. 2 is a front view of the sleeve for small glass vessel; FIG. 3 is a rear view of the sleeve for small glass vessel; FIG. 4 is a right side view of the sleeve for small glass vessel;

FIG. 5 is a left side view of the sleeve for small glass vessel; FIG. 6 is a top view of the sleeve for small glass vessel; and, FIG. 7 is a bottom view of the sleeve for small glass vessel. The broken line elements in all views are for illustrative and environmental purposes only and form no part of the claimed design.

1 Claim, 1 Drawing Sheet
